PACKSACK

Arthur C. Bernau, Sioux Falls, S. Dak.

Application June 28, 1946, Serial No. 680,123

3 Claims. (Cl. 224—8)

1

This invention relates to knapsacks and more particularly to packsacks, such as are carried by hunters, sportsmen, prospectors, and the like.

A main object of the invention is to provide a novel and improved packsack which is simple in construction, easy to carry and which is very durable.

A further object of the invention is to provide an improved packsack adapted to accommodate a wide range of different items of outdoor equipment which is substantially waterproof, arranged for convenient portage, and which is relatively inexpensive to manufacture.

Further objects and advantages of the invention will become apparent from the following description and claims and from the accompanying drawings, wherein:

Figure 1 is a front elevational view of a pack-sack constructed in accordance with the present invention.

Figure 2 is a rear elevational view of the pack-sack of Figure 1.

Figure 3 is a side elevational view of the pack-sack of Figure 1.

Figure 4 is a vertical cross-sectional view taken on line 4—4 of Figure 3.

Figure 5 is a vertical cross sectional view taken on line 5—5 of Figure 4.

Figure 6 is an enlarged detail cross sectional view illustrating the method of reinforcing the free edges of the various elements employed in the packsack of Figure 1.

Referring to the drawings 11 designates the main body of the packsack, said main body being generally rectangular in shape and being fabricated of heavy waterproof and mildew-proof canvas parts sewn together to provide a main compartment 12. The front wall 13, bottom wall 14 and rear wall 15 are preferably in one piece, and sewn to the side edges thereof on the side walls 16, 16 to provide a generally rectangular, box-shaped container. The bottom is reinforced by an additional inner thickness of heavy canvas 17 having upturned edge portions 18 overlying and extending around the bottom edge portions of the container and stitched thereto.

Stitched to the upper portion of rear wall 15 are a pair of wide canvas webbing straps 19, 19, the straps passing through a rectangular reinforcing plate of heavy leather 20 stitched to the outer surface of wall 15. Wall 15 is further reinforced at this region by an additional reinforcing plate 21 of heavy leather positioned on the inner surface of wall 15 and stitched through the wall to outer reinforcing plate 20.

2

Stitched to the bottom of the container are a pair of heavy canvas webbing loops 22, 22, each having a D-shaped ring 23 secured therein. The respective straps 19, 19 are looped through the D-shaped rings 23, 23 and are each adjustably fastened by a buckle 24. In carrying the pack-sack the respective straps 19, 19 are slipped over the user's shoulders and adjusted to convenient length by buckles 24.

Stitched to each side wall 16 is a bellows type pocket 25 provided with a cover flap 26 which extends laterally of the pocket a substantial distance on each side to prevent the entry of rain or snow into the pocket. Flap 26 is provided with a pair of leather fastening straps 27, 27 which are engageable with securing buckles 28, 28 provided on pocket 25.

Stitched to the outer surface of the upper portion of each side wall 16 is a piece of heavy canvas 29. Stitched to the inside surface and to piece 29 is a canvas reinforcing member 30. The canvas member 29 carries a pair of grommets 31, 31 in each of which is secured a leather thong 32. The leather thongs 32, 32 are employed to tie equipment over the top of the pack such as a raincoat, a bed roll, or the like.

Stitched to the lower portion of front wall 13 is a large bellows type canvas pocket 33 provided with a laterally extended cover flap 34 having fastening straps 35, 35 which are engageable with securing buckles 36, 36 carried by pocket 33.

Stitched to front wall 13 above pocket 33 is a large piece of heavy canvas 37 reinforced by an inner canvas piece 38 stitched thereto through wall 13. Canvas piece 37 carries a plurality of spaced grommets 39 having leather thongs 40 secured therein for fastening a hand axe or other implements to the pack.

Stitched to the top portion of rear wall 15 and adapted to overlie the top of the main compartment 12 is a canvas cover flap 41, said cover flap being laterally extended a substantial distance on each side of the pack to exclude rain and snow. Secured to the free edge of flap 41 by grommets 42, 42 are thongs 43, 43 which are respectively engageable with D-shaped rings 44, 44 secured to bottom element 14 for fastening the cover flap in closed position.

Stitched to the upper portion of the inside surface of the main compartment 12 around its periphery is a throat 45 of light weight waterproof canvas which is adapted to be tied at its top portion with cloth tape 46 to keep out rain and moisture.

Within the main compartment immediately

below throat 45 is provided a horizontally extending rope 47 secured by grommets 48, 48 to rear wall 15 adjacent the respective side walls 16, 16. Rope 47 provides a means of hanging a folded blanket or other soft object over it, so that the blanket or other soft object may hang down inside the pack while it is being filled, thereby providing a smooth yieldable pad and making the pack more comfortable to carry. The rope 47 also holds the blanket or other folded object in position and prevents it from slipping out of place.

Secured to each vertical front edge of the pack are one or more D-shaped rings 49 which may be employed to tie equipment to the pack or to fasten the pack to a packboard if desired.

The free edges of the cover flaps and other elements of the knapsack are preferably reinforced by sewing a small rope 50 in the hem of each free element, in the manner illustrated in Figure 6. In the case of the main cover flap 41 the grommets 42, 42 are located adjacent the reinforcing rope at the hem of the cover so that the pull of the grommet is on the reinforcing rope. The rope also stiffens the cover flap.

The large front pocket 33 and the side pockets 25 are employed to carry small articles such as cameras, maps, notebooks, fishing tackle, first aid kits, shotgun shells, and other miscellaneous items.

While a specific embodiment of a knapsack has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. A knapsack comprising a container having flexible front, rear, side and bottom walls, a pair of adjustable shoulder straps secured to the rear wall, a flexible cover flap secured to the upper portion of the rear wall and formed to overlie the top of the container, means for securing said cover flap in its overlying position, auxiliary closure means in the upper end of the container, and a rope element secured at its ends to said rear wall immediately below said auxiliary closure means and extending transversely across the top portion of the inner-side of said rear wall for substantially the full width thereof.

2. A knapsack comprising a container having flexible front, rear, side and bottom walls, a pair

of adjustable shoulder straps secured to the rear wall, a flexible cover flap secured to the upper portion of the rear wall and formed to overlie the top of the container and to extend laterally thereof for a substantial distance on each side, means for securing said cover flap in its overlying position, a throat-like flap of flexible material secured to the upper inner wall surfaces of the container, means for closing said throat-like flap, and a rope element secured at its ends to the inside surface of the rear wall immediately below said throat-like flap, said rope element extending horizontally across said rear wall for substantially the full width thereof.

3. A knapsack comprising a container having flexible rear, bottom and front walls constituting a single piece of material, side-walls secured at their edges to corresponding edges of said rear, bottom and front walls to provide a generally rectangular, box-shaped container, a pair of shoulder straps having corresponding ends secured to the upper of said rear wall and their opposite ends adjustably secured to the bottom of said container, a flexible cover flap secured along one edge to the upper edge of said rear wall to overlie the upper open end of said container, an internal closure comprising a throat-like flap of flexible, waterproof material secured around the inner-sides of said container walls adjacent the open end of said container and closable immediately below said cover flap, and a rope element extending across the inner-side of the upper portion of the rear wall of said container to support a folded blanket in position to provide a cushion at the inner-side of said rear wall.

ARTHUR C. BERNAU.
